CLAIM

The ornamental design for a cell flow channel, as shown and described.

DESCRIPTION

FIG. 1 is a front, top, right perspective view of a cell flow channel, showing our new design;

FIG. 2 is a front, top, left perspective view thereof;

FIG. 3 is a front, bottom, right perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines in the figures illustrate portions of the cell flow channel that form no part of the claimed design.
